A. V. SCHOONMAKER.

DRESS TRIMMING.

0. 18,434.

Patented July 3, 1888

UNITED STATES PATENT OFFICE.

ANNIE V. SCHOONMAKER, OF NEW YORK, N. Y., ASSIGNOR TO DUNHAM,
BUCKLEY & CO., OF SAME PLACE.

DESIGN FOR DRESS-TRIMMING.

SPECIFICATION forming part of Design No. 18,434, dated July 3, 1888.

Application filed February 21, 1888. Serial No. 264,874. Term of patent 3½ years.

To all whom it may concern:

Be it known that I, ANNIE V. SCHOONMAKER, of the city, county, and State of New York, have invented and produced a new and 5 original Design for Dress-Trimming, of which the following is a specification, reference being had to the accompanying drawing, forming a part thereof.

My invention relates to a design for dress-trimmings, the leading features of which consist of a braid-like line and a series of spirals representing snail-like figures along the edge of the braid-like line.

The photograph represents a plan view of 15 the various separate figures and the proposed grouping of the same.

The skirt figure A consists of spaced and slightly diverging braid-like lines *a*, represented as terminating at the extremities widest 20 apart in inwardly curved hook-like figures *a'*, represented as intersecting each other, the space between the said braid-like lines *a* from one end to the other containing a series of connected diamond-like figures, B. Upon the outer 25 edges of the braid-like lines *a* similar braid-like lines are formed in spirals to represent a series of gradually diminishing snail-like figures, C, each of which groups of spirally arranged lines is represented as connected by loop-like 30 figures C'.

The waist-figures D consist of a gradually-

curved braid-like line, *d*, upon the concave edge of which similar braid-like lines are drawn to represent at the ends loop-like figures *d'*, a series of uniform snail-like figures, *d''*, and 35 larger similar figures, *d'''*, which larger figures are represented as united by loop-like figures *d''* and surmounted by leaf-like figures *d''''*.

The cuff figures E consist of an irregular base, representing braid-like lines arranged in 40 spiral figures *e*, grouped to have the center figures slightly elevated. The cuff figures are completed by the addition to the base of a central spear-like figure, *e'*, and a snail-like figure, *e''*, represented as one upon each side, and 45 the whole figure E as drawn from one variously curved braid-like line.

The collar figure F consists of a braid-like line drawn to represent a united series of spiral or snail-like figures, *f*. 50

I claim—

The design for dress trimming herein shown and described, consisting of spaced and diverging braid-like lines, a series of diamond-like figures between the said lines, and a series of 55 graduated spirals representing snail-like figures along the outer edges of the braid-like lines.

ANNIE V. SCHOONMAKER.
